UNITED STATES PATENT OFFICE

MIKE MARTZ, OF HARRISBURG, PENNSYLVANIA

RAIL ANCHOR

Application filed May 18, 1931. Serial No. 538,296.

My present invention has reference to a rail anchor, my object being the provision of a rail anchor that is constructed of spring steel, to include a flat body having an offset angle notched end to receive therein one end of the base flange of a rail, its second end being formed with a looped or C-shaped portion that receives therein the second edge of the base flange of the rail and which looped portion has screwed through its outer end a bolt that contacts with the rail at the juncture of the rail with the base flange and the web thereof and is held against the web by the spring action of the loop, such spring pressure also forcing the notched end of the anchor into tight engagement with the second edge of the base flange, so that the anchor is automatic in its action in holding itself upon the rail or preventing the rail from creeping, and further wherein the construction of the rail anchor is such as to render the same long lived and to permit of the replacement of other bolts when the original bolt carried thereby is worn, so that the anchor is economical in construction, may be easily manufactured and will automatically perform its functions with ease and with accuracy.

To the attainment of the foregoing the invention consists in the improvement herein after described and definitely claimed.

In the drawing:

Figure 1 is a side elevation with the improvement in applied position, the rail being in section.

Figure 2 is an end view thereof.

Figure 3 is a sectional view approximately on the line 3-3 of Figure 1.

Figure 4 is a plan view showing the anchor applied on a rail and in contact with the ties for preventing the longitudinal movement or creeping of the rail.

The anchor is of spring metal and includes a rectangular body plate 1 having an angle end which provides a lug 2 which is notched, as at 3, to receive the edge of the base flange of a rail 4 therein. The second end of the body is formed with a loop that is substantially C-shaped and which is indicated by the numeral 5. The open portion or mouth

of the loop receives the outer edge of the base flange of the rail therein and the upper end or extremity of the loop 5 merges into a rounded portion or boss 6 that is provided with a threaded bore. Screwed through this

bore there is the shank of a bolt 7. Even before the bolt is applied the upper arm of the loop is in frictional contact with the base flange and with the web of the rail to force the notched portion 3 of the lug 2 into engagement with the second or inner edge of the base flange of the rail, but when the bolt

6 is screwed to contact with the wall at the juncture of the base flange and web of the rail the loop will be expanded and spread upwardly and outwardly with respect to the rail and consequently will draw upon the body plate to force the latter into tight contact with the under face of the base of the rail and likewise force the hooked end of the

70 anchor into tight gripping engagement with the edge of the base flange of the rail with which it engages and thereby effectively and automatically sustain the anchor in position on the rail. By reference especially to Fig.

75 ure 1 of the drawing it will be noted that the C-shaped or looped portion 5 is of a less width than the body 1, as is also the portion of the body formed with the notched lug

2. The ends of the body plate are, therefore, 80 of greater resiliency than the body plate proper. The anchors are applied on the rail to contact with the opposite or outer faces of the ties or sleepers 8 upon which the rails rest and are spiked. The anchors prevent

85 the longitudinal creeping movement of the rails. Should the bolts 7 become worn or damaged new ones can be supplied to readily replace such worn or damaged bolts without necessitating the discarding of the anchor

90 which is not true with respect to the majority of such devices. The anchor may be economically constructed and cheaply marketed and the ease of application and the efficiency thereof will, it is thought, be understood and

95 appreciated.

Having described the invention, I claim:

A rail anchor designed to contact with a tie to hold the rail from longitudinal creeping, said anchor comprising a metal spring

member which includes a substantially rectangular body portion to underlie and to contact with the base of a rail for a distance greater than one-half of the length of the base of said rail, said body plate having both of its ends reduced in width and one of said ends being formed with an upstanding lug which is notched to receive one edge of the base flange of the rail therein, the second end 5 of the plate being substantially C-shaped and receiving therein the second edge of the base flange of the rail, the outer and upper end of C-shaped portion being formed with a boss which is arranged at an angle with respect 10 to the body plate and which boss has a threaded bore and a headed bolt screwed through said bore to contact with the rail at the juncture of the base flange and web thereof and said bolt also designed to expand 15 the upper arm of the C-shaped end of the plate to force the body plate into tight gripping engagement with the under face of the rail.

20

In testimony whereof I affix my signature.

25 MIKE MARTZ.
